UNITED STATES PATENT OFFICE.

ALEXANDRE M. GREAN, OF NEW YORK, N. Y.

SHOULDER AND SLEEVE FORM.

No. 810,333.

Specification of Letters Patent.

Patented Jan. 16, 1906.

Application filed June 12, 1905. Serial No. 264,958.

To all whom it may concern:

Be it known that I, ALEXANDRE M. GREAN, a citizen of the United States, residing in the borough of Manhattan, city, county, and State of New York, have invented a useful and new Improvement in Shoulder and Sleeve Forms, obviating the necessity of the use of bulky, cumbersome, and unwieldly hair cloth and woolen paddings at present used; and I do declare the following to be a clear and exact description of the nature thereof, so that those skilled in the art to which my invention applies may make, use, and fully understand the same, reference being had to the accompanying drawings, which are part of this specification, and are fully described, and defined specifically in the claims of this application.

This invention relates to shoulder-forms, and pertains especially to the class of such forms adapted to be made up with and form a part of personal wearing-apparel.

The object of the invention is to provide a shoulder-form the length of which may be varied as desired and having an extension or wing projecting therefrom for holding a garment-sleeve in graceful position from the shoulder.

A further object of the invention is to provide a shoulder-form having a wing or extension projecting upwardly and outwardly from its outer end for the purpose of holding a garment-sleeve in proper position.

With these and various other objects in view the invention consists of a shoulder-form shaped to fit closely the lines of a person's shoulder and adapted to produce in a garment a shoulder perfect in shape and form and a wing or extension projecting from the form into the garment-sleeve to expand and hold the latter in proper position.

In the accompanying drawings, forming part of this application, Figure 1 is a front view showing the application of the invention. Fig. 2 is a perspective view of the shoulder-form. Fig. 3 is a longitudinal section. Fig. 4 is a side elevation showing the wing turned back.

The same numeral references denote the same parts throughout the several views of the drawings.

The shoulder-form may be made of tailor's canvas, felt, or any other suitable material adapted to be shaped to desired position and to be sewed into the lining of a garment. The body 1 is semicircular-shaped in cross-section 55 and is provided with a series of pads 2 to elevate the shoulder of a garment as desired. The arm 3 of the form is concaved centrally and tapers to its end 4, which may be cut off to shorten its length as desired or as occasion may demand. The edges 5 curve inwardly at the body 1 and terminate at the end 4. This construction will be found to fit the shoulders of various persons by very little shaping of the form. 60 65

The sleeve-holder consists of a hood-shaped wing or extension 6, projecting outwardly and upwardly from the body 1, so as to over-reach the shoulder and, especially in women's garments, extend the sleeve at the shoulder 70 and hold it in graceful position. When the wing is not to be used for a sleeve, it may be turned back upon the body 1, and thereby help the latter to fill out the shoulder of a garment. 75

Having thus described my invention, what I claim as new, and desire to secure by Letters Patent, is—

1. As a new article of manufacture, a shoulder-form for garments comprising a tapering 80 portion adapted to extend into the shoulder of the garment, and a wing extending upwardly and outwardly from and at an angle to said portion.

2. As a new article of manufacture, a shoulder-form for garments, comprising a shoulder portion having a tapering arm adapted to extend the length of the shoulder, and a wing extending throughout the outer edge of the shoulder portion and projecting from the latter upwardly and outwardly in circular shape. 85 90

In testimony whereof I have hereunto signed my name to the foregoing specification in the presence of two subscribing witnesses.

ALEXANDRE M. GREAN.
